UNITED STATES PATENT OFFICE.

EMANUEL M. HACKER, OF NEW YORK, N. Y.

DESIGN FOR PLAITING.

41,048.

Specification for Design. Patented Dec. 13, 1910.

Application filed March 28, 1910. Serial No. 552,120. Term of patent 14 years.

To all whom it may concern:

Be it known that I, EMANUEL M. HACKER, a subject of the King of Hungary, having taken out my first papers in the United States, and residing in the city, county, and State of New York, have invented a new, original, and ornamental Design for Plaiting, of which the following is a specification, reference being had to the accompanying drawing, forming part thereof.

The figure is a view of a piece of dress fabric plaited in accordance with my new design.

I claim—

The ornamental design of plaiting substantially as shown.

EMANUEL M. HACKER.
